UNITED STATES PATENT OFFICE.

HERBERT TIDMARSH GEORGE, OF LONDON, ENGLAND, ASSIGNOR TO ARNOLD, CONSTABLE & CO., OF NEW YORK, N. Y.

DESIGN FOR A CARPET.

SPECIFICATION forming part of Design No. 21,857, dated September 13, 1892.

Application filed August 17, 1892. Serial No. 443,351. Term of patent 3½ years.

To all whom it may concern:

Be it known that I, HERBERT TIDMARSH GEORGE, a subject of the Queen of Great Britain, residing at 16 Dickenson Road, in the county of London, England, have invented and produced a new and original Design for a Carpet; and I do hereby declare that the drawing accompanying this specification conveys to any one skilled in the art a clear understanding of the same and is sufficient to enable such persons to use my invention.

What I claim as my invention, and desire to secure by Letters Patent, is—

The design for carpets, consisting of the ornate-ments shown in the drawing accom- 15
panying this specification.

HERBERT TIDMARSH GEORGE.
